UNITED STATES PATENT OFFICE.

JAMES A. GREEN, OF TORRINGTON, CONNECTICUT, ASSIGNOR TO THE TURNER & SEYMOUR MANUFACTURING COMPANY, OF TORRINGTON, CONNECTICUT, A CORPORATION OF CONNECTICUT.

FURNITURE SLIDE AND METHOD OF MAKING SAME.

Application filed April 23, 1923. Serial No. 633,890.

To all whom it may concern:

Be it known that I, JAMES A. GREEN, a citizen of the United States, and resident of Torrington, county of Litchfield, and 5 State of Connecticut, have invented certain new and useful Improvements in Furniture Slides and Methods of Making Same, of which the following is a specification.

The invention relates to a furniture slide 10 and method of making same. The objects of the invention include the provision of a novel and efficient form of furniture slide or glide which shall be efficient in operation and comparatively inexpensive to 15 manufacture, and the provision of improved methods by which the same may be made and assembled. Other objects comprise improved combinations and details of construction and of the manufacturing 20 process as will be more fully pointed out in the following specification.

In order that the invention may be more clearly understood attention is hereby directed to the accompanying drawings forming 25 part of this application and illustrating a furniture slide embodying the invention and certain steps of a process by which the same may be made. Referring to the drawings—

30 Fig. 1 represents a vertical section taken through a solid member which is to form the slide, the axial shank which is to be secured thereto being shown in dotted lines;

Fig. 2 is a vertical section taken through 35 the solid head or body after the shank has been secured thereto, the shank being shown in side elevation, and

Fig. 3 is a top plan view of the complete slide shown in Fig. 2.

40 Referring to the drawings, the slide comprises a solid integral metal head 1, having a smooth bottom or sliding surface upwardly curved around the outer edge thereof as indicated at 3. The head is provided

45 with a plane upper surface 4 having one or a plurality of projections extending upwardly therefrom, preferably for a slight distance only, which are intended to engage the lower surface of the wooden leg, 50 or other surface of the furniture to which the slide is applied to prevent turning of the slide when it has been applied. Preferably these projections take the form of a

plurality of slight radial ribs, or ridges, 5, which extend inwardly for a part of the 55 distance between the outer edge 6 of head 1 and the vertical axis thereof. The slide is provided with a shank 7 extending upwardly from the center of the upper surface thereof, this shank preferably being 60 formed as a separate member having a head or enlarged lower end 8 embedded within the metal of the sliding head 1.

Preferably the head 1 is formed of steel or other suitable metal and the shank 8 65 is formed of steel wire or other suitable metal having the same coefficient of expansion or substantially the same coefficient of expansion as the metal of which the head 1 is composed. The head 1 is preferably 70 pressed to form, as shown in Fig. 1, with a cylindrical opening 9 extending downwardly for a distance from the upper surface 4 thereof, this recess being coaxial with the head 1. 75

The heads or blanks are preferably formed and pressed to shape complete as shown in Fig. 1 from suitable material the ribs 5 being formed integral with the head. The blanks are then preferably fed automatically to another machine where the shanks are formed and automatically assembled to the heads. A shank having its head 8 positioned within the opening 9 may be secured to the head by forcing the metal 80 of the head surrounding opening 9 downwardly over the head 8 of the shank so as to completely cover the head 8 of the shank and secure the shank firmly in position. This may readily be done by a swaging 85 operation, the result being the provision of a slight circular depression 10 surrounding the shank 7, the metal within which circular depression has been forced downwardly over the head 8 of the shank from its 90 former position surrounding the opening 9, as shown in Fig. 1. 90

The formation of the shanks and the assembly of the same with the heads is preferably carried on continuously and automatically in the one machine, as stated. Each shank being cut to length from a coil of wire and pointed at its upper end, as shown at 11, may have its head 8 formed thereon by an upsetting operation preferably after 100 the lower end of the shank has been inserted 105

- within opening 9, the lower end of the shank being sufficiently upset to cause the upset end 8 thereof to completely fill the opening from side to side after which the metal 5 of the head 1 is swaged down over the shank head 8, as stated. It is thought unnecessary to disclose herein the exact details of mechanism by which this process is carried out in practice.
- 10 The slide is applied to furniture by simply driving the same into position therein, the shank 7 preferably being scored or roughened as indicated at 12 to prevent the same from working out. The ribs 5 penetrate 15 slightly into the wood to prevent turning and loosening of the slide, the height and thickness of the ribs being insufficient, however, to cause any danger of the same cracking the wood.
- 20 It will be noted that various improved results are obtained by a construction such as described in comparison with the furniture slides previously made, with which I am familiar. Furniture slides, glides or tips, as 25 they are variously called, are commonly formed by pressing sheet metal into the form of a shell which may be formed of one or more sheets or thicknesses of metal commonly having prongs integral with the edge portion thereof. In such a case the shell is 30 likely to be dented when it is hammered into place unless it is made of heavy metal, in which case the prongs are liable to split the furniture leg. Also the shells being of 35 comparatively thin metal will not sufficiently resist wear unless they are hardened. The teeth or prongs at the periphery of hardened shells are likely to be brittle and break off. With such shells there has also 40 been difficulty in securing and a central nail or shank in place, when such a nail has been proposed.
- These various difficulties are all overcome by the construction described. In my 45 construction it is unnecessary to harden the steel or other metal of which the head is formed because the same is solid and has sufficient thickness to resist wear without hardened, but the head may be hardened 50 if desired. The shank is preferably formed of the same metal as the head or of a metal having the same coefficient of expansion so that the head and shank will not expand and contract unequally. The ribs 5 are not brittle or liable to break off, as is the case with 55 the integral prongs provided at the periphery of various sheet metal shells above referred to. These ribs extend inwardly for a sufficient distance to prevent turning of 60 the slide under the stresses to which it is subjected in use, while at the same time the ribs are preferably of such slight height and thickness as to have no tendency to split 65 the wood. In describing the ribs as radial I mean to include ribs extending inwardly

over the face 4 of the head in directions which may not be exactly directed towards the center, but which nevertheless will extend at a sufficient angle to a tangential turning force so as to resist turning of the 70 slide. It should be noted that the invention is not limited strictly to the details of construction which have been particularly described, but that the same is as broad as is indicated by the accompanying claims. 75

What I claim is:

1. A furniture slide, comprising a solid integral head of hard, durable metal having a smooth lower sliding surface upwardly curved around the edge, and having one or more radial upwardly extending ribs on its upper surface, and a pointed shank extending upwardly from said upper surface, said ribs being adapted to slightly penetrate the wood of the furniture, to prevent 80 the slide from turning.

2. A furniture slide, comprising a solid integral head of hard, durable metal having a smooth lower sliding surface upwardly curved around the edge, and having one or more radial upwardly extending ribs on its upper surface, extending inwardly from the edge, and a separate shank extending upwardly from the center of the upper surface, said shank having a head portion embedded 90 in the metal of said solid head.

3. A furniture slide, comprising a solid integral metal head having a smooth lower sliding surface upwardly curved around the edge, and having one or more radial upwardly extending ribs on its upper surface, extending inwardly from the edge, and a separate shank formed of metal having the same coefficient of expansion as said head, extending upwardly from the center of the 100 upper surface, said shank having a head portion embedded in the metal of said solid head, the metal of the solid head being pressed down over the said shank head portion to hold the same in place. 110

4. A furniture slide, comprising a solid steel head and a separate steel shank extending upwardly from the center of the upper surface thereof and having a head portion embedded in the metal of said solid head, said solid head having a lower sliding surface upwardly curved around the edges and having slight integral projections extending upwardly from the upper surface of the head, said projections extending inwardly part way between the outer edge and the shank, and serving to resist turning of the 115 slide. 120

5. A furniture slide, comprising a solid head of unhardened steel, and a separate steel shank extending upwardly from the center of the upper surface thereof and having a head portion embedded in the metal of said solid head, said solid head having a lower sliding surface upwardly curved 125 130

around the edge, and being of sufficient thickness to resist wear without being hardened, said head having slight integral projections extending upwardly from the upper 5 surface of the head and having such slight height and thickness as to have substantially no tendency to split the wood into which

they are driven, said projections extending inwardly part way between the outer edge and the shank, and serving to resist turning 10 of the slide.

In testimony whereof I have signed my name to this specification.

JAMES A. GREEN.
